UNITED STATES PATENT OFFICE.

HORACE G. SKIDMORE, OF CINCINNATI, OHIO.

WATCH-CASE.

SPECIFICATION forming part of Letters Patent No. 298,509, dated May 13, 1884.

Application filed January 17, 1884. (No model.)

To all whom it may concern:

Be it known that I, HORACE G. SKIDMORE, of Cincinnati, Hamilton county, Ohio, have invented a new and useful Improvement in 5 Watch-Cases, of which the following is a specification.

My invention relates to a new and useful construction, in one integral piece, of the movement-ring part and of the back-rim part 10 of a watch-case, and of the combination therewith of other useful novelties hereinafter explained.

The object of my invention is the production, at a moderate cost, of a practically dust 15 and moisture proof watch-case of great compactness, simplicity, and elegance.

My improved case being adapted to a great variety of watch-movements, none are here represented.

20 In the accompanying drawings, Figures 1 and 2 represent a form of my improvement applicable for use with a stem-winder watch of the hunter pattern, Fig. 1 showing the members detached from one another, and Fig. 25 2 being an axial section of the case in its closed condition.

A characteristic and important feature of my improvement is a peculiarly-formed annular piece of metal, A B, of which the portion 30 A serves as the ring part to hold the watch-movement, (not here shown,) and of which the portion B does duty as the rim part or frame of the back, to which latter a panel, C, is removably attached by any suitable 35 means, preferably those here shown—that is to say, the central opening of such rim part has a screw-thread, b, and a shoulder, b', to enable dust and moisture proof attachment of correspondingly threaded and shouldered 40 panel as aforesaid. The said annulus A B is removably fastened to the body or "center" D by any suitable means—as, for example, by exteriorly-threaded riser b", which screws within the corresponding interiorly- 45 threaded margin, d, of said center. A ledge, a, on the interior wall of ring part A serves, in association with customary retaining-pin and fastening-screw or other suitable means, to hold the movement accurately in place. At 50 a' and a" are seen the usual recesses for such pin and the head of such screw. An exteriorly screw-threaded riser, a'', on front edge of said ring part A enables dust and moisture

proof attachment of a correspondingly-threaded bezel, E. A riser or rabbet, d', on the outer front margin of center D enables the snapping thereto of a front cap, F, having customary hinge attachment, G, to said center. Screwing of the members C and D to and from the annulus A B may be facilitated by knurlings J.

In that form of my improvement which is designed for use with hunter cases, customary or any suitable case-springs, K L, are attached in the accustomed manner to the interior wall 65 of the center D, which center is for that purpose chambered, as represented.

When designed for a stem-winder watch, the ring part A of the annulus A B has an orifice, a^{IV}, in alignment with the axis of the pend- 70 ant H.

If preferred, the unexposed portion A of the annulus may be of cheaper metal than the other portions of that member, and be united to them by soldering.

75 A glazed bezel may be substituted for the all-metal cap C in open-faced watches.

Complete accessibility for regulating and other purposes is afforded by simple removal of the panel C without necessitating withdrawal of the movement from the case.

I claim as new and of my invention—

1. In a watch-case, the annulus A B, in which the ring part A and the back-rim part B constitute one integral piece of metal, substantially as and for the purpose set forth.

2. In a watch-case, the combination, with the case-center D and annulus A B, of the separable dust-proof panel C, substantially as set forth.

3. In a watch-case, the annulus A B and case-center D, in combination with panel C and bezel E, attached, in the manner described, at the back and at the front, respectively, of said annulus, for the purpose set forth.

4. In a watch-case, the chambered annulus A B, closed at rear and open at front, in combination with the case-springs K L, case-center D, and the pendant H, substantially as set forth.

In testimony of which invention I hereunto set my hand.

HORACE G. SKIDMORE.
